UNITED STATES PATENT OFFICE

JOHN J. HERLIHY, OF GLENWOOD, PITTSBURGH, PENNSYLVANIA

MACHINE FOR WEARING IN JOURNAL BEARINGS

Application filed December 5, 1929. Serial No. 411,821.

My invention relates to a class of machines built for the purpose of wearing in inside and outside journal bearings on the journal to which they are to be used.

5 The object of my invention is to provide means in such a machine that the journal and its bearing are worn while the wheel is in motion with the weight on the wheel and the brake cylinder pressure against the journal 10 while the bearing is being worn into the journal.

Another object of my invention is to provide means whereby the wheel journal has the same weight and thrust that it will be 15 subjected to in actual service.

Another object of my invention is to provide such a machine that the wheels and axle may be rolled into it in position from the floor of the shop; and with these and other 20 objects in view my invention consists of the parts and combination of parts hereinafter pointed out.

The machine shown for the purposes of illustrating my invention is primarily designed for operating upon car wheels and the bearings therefor.

In the drawings:

Figure 1 is a front elevation of a machine embodying my invention.

30 Figure 2 is an end elevation of Figure 1 with a car wheel and journal rolled therein.

Figure 3 is a top plan view of Figure 1.

Figures 4 and 5 respectively are top and end views of the oscillating mechanism.

35 The reference numeral 6 designates a framing, preferably set in a concrete base 7, in which I also position a wheel track 8 which, as shown in Figure 2, extends outwardly from the frame whereby car wheels

40 on axles may be rolled from the shop floor into the machine, thereby eliminating separate lifting means. The frame has a forwardly extending top 9 hollow and of built up construction, as shown in Figure 1, there

45 being a slot 10 in the bottom wall of this housing. Rollers 11 are journalled in bearings 12 in the housing 9 and project, as seen in Figure 1, below the bottom face of the housing. Preferably, there are two of these

50 rollers 11 in each housing 9, the rollers of

each pair being so spaced from each other as to insure a proper bearing on the tread of the car wheel 13.

A shelf 14 extends between the housings 9 and frames 6 on which are mounted two air 55 brake cylinders 15 which are rigidly secured in position. The piston rods 16 of the cylinders are, preferably, forked at their upper ends, and a beam or cross rail 17 is secured in the forked ends of the rods 16.

60 A hanger strap 18 is mounted on each end of the beam 17 to which the upper end of the hanger 18 is secured by bolts or rivets 19. A stirrup 20 is secured to the lower end of the hanger 18 by bolts or rivets 23 and terminates at its lower end in a forwardly extending housing 21, which is designed to receive, and, hold the journal bearing 22.

65 Some railroads use on their engine truck wheels inside bearings. To treat these on 70 my machine it is only necessary to place the hangers and their immediately attached parts in the position shown in dotted lines in Figure 1.

75 Extending upwardly from the shelf 14 are guides 24 to provide a stop, the desired distance above the beam 17, to limit the upward movement of said beam.

The frame 6 is provided with a bracket 25 on which is suitably mounted a suitable motor 26 connected with a power shaft 27 to which is keyed a pinion 28 which meshes with a gear wheel 29, and this in turn meshes with a pinion 30 keyed to the shaft 31. The rollers 11 are keyed to these shafts 27 and 31 80 whereby said rollers are positively driven.

85 The gear wheel 29 is provided with a pinion 32 which in turn meshes with a pinion 33 keyed to the stub shaft 34 having a worm 35 formed therein which meshes with a worm gear 36 carrying a post 37 having on its upper end an eccentric pin 38 which projects into a slot 42 or other opening in the bar 40, which bar is connected to the hangers 18 whereby when the bar 40 is oscillated by the eccentric pin 38 the hangers are oscillated which, in turn, causes the bearings 22 to oscillate with reference to the journal while the journal is revolving.

90 95 100 After the wheels are rolled from the shop

floor or into the machine, as shown in Figure 2, (the bearing 22 being in place) air is admitted into the air cylinders by the two way valve 41 through the pipes 43, whereupon the rods 16 are elevated carrying with them the beam 17 and hangers 18 until the treads of the wheels 13 contact with the driving rollers 11, wheels 13 are in the elevated position indicated by the dotted lines in Figure 2. The valve 41 is for the purpose of increasing or decreasing the pressure on the journal while the wheels 13 are in motion to, as nearly as possible, obtain the same weight that the wheel will have thrust upon it in actual service. The pressure in the cylinders being designated by the gauge 44.

The oscillating mechanism described is designed to oscillate the bearing 22 back and forward on the journal while the wheel 13 is rotating in order that the journal and bearings will have a motion in the machine such as it has in actual service.

As stated, the machine is designed to take care of the inside and the outside bearings.

This machine breaks the journal in properly to the brass 22, so that when the journal and brass are placed in actual service the journal will run without heating, thus eliminating delays and failures on the line of road due to heated bearings. The actual condition of the bearings and journal can be developed in this machine before the journal and bearings are placed in actual road service, thus all corrections are made before the journal and bearing are put in service.

The bar 40 is provided with a series of bolt openings 45 at each end. To transmit the reciprocatory movement of the bar 40 to the hangers 18 I secure a block 45' to the bar by means of bolts 46, said block having an elongated opening 47, through which the bolts pass, said elongated opening providing for adjustment of the block 45' relative to its bolts for position to engage the hangers. The block 45' is provided with rearwardly extending arms 48 which engage and extend on each side of the hangers 18 so that as the bar 40 reciprocates its movement is transmitted through the arms 48 of the block 47 to the hangers 18.

The series of bolt holes 45 permit of readily positioning the blocks 47 on the bar 40 for adjustment of the hangers 18 to fit various lengths of axles in inside and outside journals. The pin 38 is provided with a bushing 49.

What I claim is:

1. In combination, in a machine for wearing journal bearings on the journals with which they are to be used, a frame, driving rollers on the frame, a wheel supporting carriage vertically adjustably supported in said frame for moving the wheel carrying the journal toward and from the rollers, a jour-

nal bearing supporting means carried by said carriage.

2. In combination, in a machine for wearing journal bearings on the journals with which they are to be used, a frame, driving rollers on the frame, a carriage vertically adjustably supported in said frame for moving the wheel carrying the journal toward and from the rollers, a journal bearing supporting means carried by said carriage, and means to raise and lower said carriage and support the carriage in its adjusted position.

3. In combination, in a machine for wearing journal bearings on the journals with which they are to be used, a frame, driving means on the frame, a carriage vertically adjustably supported in said frame for adjusting the journal toward and from the driving means, a journal bearing supporting means carried by said carriage, means for driving the driving means to revolve the journal on said bearing, and means for oscillating the bearing while the journal is being revolved.

4. In combination, in a machine for wearing journal bearings on the journals with which they are to be used, a frame, a beam vertically adjustably supported in said frame, a journal bearing supporting means carried by said beam, and means to revolve the journal on said bearing, and means to oscillate the bearing back and forth on the journal while the journal is being revolved.

5. In combination, in a machine for wearing journal bearings on the journals of wheels with which they are to be used, a frame, a vertically adjustable support on said frame, a hanger secured to said support, and a journal bearing means carried by said hanger.

6. In combination, in a machine for wearing journal bearings on the journals of wheels with which they are to be used, a frame, a vertically adjustable support on said frame, a hanger secured to said support, and a journal bearing means carried by said hanger, driving rollers mounted in fixed relation to said frame designed to bear on the tread of a wheel while said journal is wearing in the bearing.

7. In combination, in a machine for wearing journal bearings on the journals of wheels with which they are to be used, a frame, a vertically adjustable support on said frame, a hanger secured to said support, and a journal bearing means carried by said hanger, driving rollers mounted in fixed relation to said frame designed to bear on the tread of a wheel while said journal is wearing in the bearing, and means to reciprocate said hangers axially with reference to the journal supported therein.

8. In a machine for wearing journal bearings on the journals with which they are to be used, the combination of a supporting frame for holding an axle, its wheels, jour-

nals and journal bearings, driving rollers on the frame, fluid pressure actuated means for moving said frame to press the wheels into driving engagement with the rollers, 5 means for reciprocating the frame to move the journal bearings back and forth over the faces of the journals, and means for driving the rollers.

9. In a machine for wearing journal bearings on the journals with which they are to be used, the combination of a supporting frame, a shaft mounted on said frame, driving rollers carried by said shaft, a vertically movable carrier frame on the supporting 15 frame for holding an axle, its wheels, journals and journal bearings, fluid pressure means for actuating the carrier frame to press the wheels into driving engagement with the rollers, means for driving the axle, and means 20 for reciprocating the carrier frame to move the journal bearings back and forth over the faces of the journals.

In testimony whereof I affix my signature.
JOHN J. HERLIHY.
